UNITED STATES PATENT OFFICE.

ARTHUR A. MCRAE, OF ATTLEBORO, MASSACHUSETTS, ASSIGNOR TO MCRAE AND KEELER, OF SAME PLACE.

DESIGN FOR A SPRING-SUPPORT FOR ORNAMENTS OF HAT-PINS OR SIMILAR ARTICLES.

SPECIFICATION forming part of Design No. 34,896, dated April 23, 1901.

Application filed March 20, 1901. Serial No. 52,101. Term of patent 7 years.

To all whom it may concern:

Be it known that I, ARTHUR A. MCRAE, a citizen of the United States, residing at Attleboro, in the county of Bristol and State of Massachusetts, have invented and produced a new and original Design for a Spring-Support for the Ornaments of Hat-Pins or Similar Articles, of which the following is a specification, reference being had to the accompanying drawings, forming part thereof.

Figure 1 is a side view of a spring-support for the ornaments of hat-pins and similar articles. Fig. 2 is an end view on an enlarged scale, and Fig. 3 is a longitudinal sectional view of the same.

The invention relates to the ornaments used on hat-pins and similar hat or hair ornaments, which are at times supported on springs to impart a tremulous movement to the ornament.

As shown in the drawings, the leading and

material feature of my design consists in the bulbous-shaped outline of the spiral wire spring, presenting to the eye the appearance of a flower or seed-bulb. The lower stem-like end enlarges gradually into a bulb, contracting toward the upper end to about half the greatest diameter of the bulb.

Having described my invention, what I claim as new, and desire to secure by Letters Patent, is—

The design for the spring-support of the ornaments of hat-pins and similar articles, as herein shown and described.

In testimony whereof I have signed my name to this specification in the presence of two subscribing witnesses.

ARTHUR A. MCRAE.
